UNITED STATES PATENT OFFICE.

JOSEPH A. JOHNSON, OF KNIGHT, WYOMING.

AX.

Application filed March 5, 1921, Serial No. 449,761. Renewed October 9, 1922. Serial No. 593,441.

To all whom it may concern:

Be it known that I, JOSEPH A. JOHNSON, a citizen of the United States, residing at Knight, in the county of Uinta and State of Wyoming, have invented a new and useful Ax, of which the following is a specification.

The object of my invention is to provide an ax having a removable bit and means for the convenient removal and replacement 10 of such bits, whereby to require a minimum of steel for the ax and the convenient replacing of a dulled bit by a sharp one without requiring a visit to the grindstone.

I attain these and other objects of my invention by the device illustrated in the accompanying drawings, in which—

Figure 1 is a side elevation of the device ready for use;

Fig. 2 is a longitudinal section on the line 2—2 of Fig. 4, approximately, when the bit is applied to the ax body;

Fig. 3 is a front elevation of the ax body 1 when the bit 2 is removed; and

Fig. 4 is a rear elevation of the bit 2 when 25 it is removed from the ax body.

Like numerals designate like parts in the several views.

Referring to the accompanying drawings, I provide an ax body 1 of any desired shape 30 as to its general contour, said body being of malleable iron. Ax body 1 is provided with projections 3, which have beveled edges 7, as shown in Fig. 3, and with the projection 11, and a corresponding cut-out portion 10 35 on the other side of the interlocking portion of the ax body. I further provide the cylindrical recesses 9 in projection 3 and recessed portion 4, as shown in Fig. 3.

I further provide, as a new article of manufacture, a detachable steel bit adapted to be removably attached to the malleable iron ax body 1, and for this purpose I provide the projection 6 having beveled edges 7, said projection being of corresponding shape to 45 the recess 4 in the ax body, and having a cylindrical stud 8 shaped to seat in the recess 9; also I provide a similar stud 8 in the recess portion 5 to interlock with the recess 9 and projection 3 of the ax body. I 50 also provide the projection 11 adapted to seat in recess 10 of the ax body; and a recess 10 to receive the projection 11 of the ax body; thus providing overlapping members at both the distal and proximal edges of the 55 ax body and bit. I further provide orifices 14 extending through members 11 and 13

at both the distal and proximal edges of the ax, said orifices 14 being countersunk at each side to receive suitable small rivets 12, as shown in Figs. 1 and 2. In using my invention the lumberman carries a number of the steel bits 2 so that when the cutting edge of one bit gets chipped, broken, or worn out, it can readily be detached and replaced by a fresh steel bit, thus making an ax that is 60 far cheaper in the long run than the conventional ax, and eliminating the loss of time and trouble of frequently sending the ax to the grindstone, as heretofore.

I am aware that axes have heretofore been 70 made having certain resemblances to this device, but without the convenient detachable bit of steel on a malleable iron or soft steel body, which is the novel feature, in connection with the improved means for attaching and detaching same, disclosed in my invention, and which distinguishes it from various axes that are made by pouring the iron through the bit in manufacturing, and which are solid when finished. 80

What I claim is:

1. In an ax, the combination of a body of malleable iron or soft steel, said body having a series of aligned diagonally bevelled projections and recesses and also having angularly recessed portions adjacent the distal and proximal edges of the ax, and a relatively narrow steel bit having corresponding projections and recesses adapted to seat in and interlock with the recesses and projections of the ax body, and means for riveting the overlapping portions of the bit and ax body together to provide a replaceable bit. 85

2. As a new article of manufacture, a narrow detachable steel bit adapted to be removably secured to an ax body suitably shaped to receive same but of less expensive material, the ax bit having an intermediate projection having parallel diagonally bevelled sides, and having opposite end projections, one of said projections having a side bevelled diagonally and in a reverse direction to that of the intermediate projection. 95

3. As a new article of manufacture, a narrow detachable steel bit adapted to be removably secured to an ax body of less expensive material, said bit having a plurality of projections, two of the projections having reversely bevelled lateral faces, the projections including oppositely disposed end projections extending part way across the 105 110

bit only and having recesses for rivets to engage the body of the bit in corresponding projections thereof, the bit also having studs adapted to engage in recessed portions 5 of the body of the ax.

4. In an ax, the combination of a body, said body having a series of projections, two of the projections having their faces 10 reversely bevelled, the ax also having recessed openings for studs, and a steel bit of rela-

tively narrow width throughout, said bit having a series of projections and recesses adapted to interlock with the recesses and projections of the ax body and including oppositely bevelled lateral faces on two of 15 the projections, central studs positioned to project into recessed portions of the ax body, and means for releasably riveting the bit to the ax body, substantially as described.

JOSEPH A. JOHNSON.
